US00D524825S

(12) **United States Design Patent** (10) Patent No.: **US D524,825 S**
(45) Date of Patent: **** Jul. 11, 2006**

(54) **CENTRIFUGE SUPPORT**

(75) Inventors: **Richard James Koch**, Magnolia, TX
(US); **Hubert Frank Baker**, Bellaire,
TX (US)

(73) Assignee: **Varco I/P, Inc.**

(**) Term: **14 Years**

(21) Appl. No.: **29/179,166**

(22) Filed: **Apr. 5, 2003**

(51) **LOC (8) CL.** **15-03**

(52) **U.S. CL.** **D15/21**

(58) **Field of Classification Search** **D15/10,**

(57) **CLAIM**

The ornamental design for a centrifuge support, as shown and described.

DESCRIPTION

FIG. 1 is a rear view of a centrifuge support showing our new design.

FIG. 2 is a top view thereof.

FIG. 3 is an end view thereof.

FIG. 4 is a front view thereof.

FIG. 5 is an end view opposite that of FIG. 3; and,

FIG. 6 is a bottom view thereof.
